UNITED STATES PATENT OFFICE.

ADOLPH C. RECKER, OF OAKVILLE, CONNECTICUT, ASSIGNOR TO WATERBURY MFG. CO.,
OF WATERBURY, CONNECTICUT, A CORPORATION.

PORTABLE ELECTRIC LAMP.

1,113,909.

Specification of Letters Patent. Patented Oct. 13, 1914.

Application filed May 15, 1914. Serial No. 838,680.

To all whom it may concern:

Be it known that I, ADOLPH C. RECKER, a citizen of the United States, residing at Oakville, in the county of Litchfield and State of Connecticut, have invented a new and useful Improvement in Portable Electric Lamps; and I do hereby declare the following, when taken in connection with the accompanying drawings and the characters of reference marked thereon, to be a full, clear, and exact description of the same, and which said drawings constitute part of this application, and represent, in—

Figure 1 a side view of a portable electric lamp constructed in accordance with my invention. Fig. 2 a vertical sectional view of the same on an enlarged scale.

My invention relates to an improvement in portable electric lamps in which the casing is tubular, simulating in appearance a candle, the object of this invention being to provide a portable electric lamp in the form of a candle and candle-stick; and the invention consists in the construction hereinafter described and particularly recited in the claims.

In carrying out my invention the candle-stick is struck up from sheet metal forming a base 2 to which a handle 3 is applied. The central portion 4 of the top of the base is raised and upon this is mounted a cup-shaped shell 5 in the bottom of which is a socket 6 the center of which is raised forming a pressure point 7. The socket is screw threaded to receive the threaded lower end of a casing 8 which is provided in its upper end with an incandescent lamp 9 and adapted to receive a cylindrical battery 10. Between the battery and the upper end of the casing 40 is a spring 11 the tendency of which is to force the battery downward and out of contact with the lamp. By screwing the casing 8 into the socket 6 the battery comes to a bearing on the pressure point 7 and is forced

upward against the pressure of the spring 45 11 until the upper end contacts with the lamp and so closes the circuit, and to extinguish the lamp it is only necessary to turn the shell sufficiently to allow the battery to drop away from contact with the lamp 50 and thereby open the circuit. I thus provide in a very inexpensive form a portable electric lamp in the form of a candle and candle-stick in which the circuit may be closed by simply turning the shell into its 55 socket.

I claim:—

1. A portable electric lamp comprising a candle-stick provided with a metal socket having a pressure point, a casing adapted 60 to be turned into said socket, an incandescent bulb mounted in the upper end of the casing, a battery in the casing and resting on said pressure point, and a spring between the top of the battery and the casing 65 adapted to be compressed by turning the casing into the socket.

2. A portable electric lamp comprising a candle-stick having a base formed from sheet metal, a cup-shaped shell mounted on 70 said base, a metal socket within said shell and formed in its bottom with a pressure point, a tubular casing adapted to be turned into said socket, said casing provided at its upper end with an incandescent lamp, a 75 battery within said casing and resting on said pressure point, a spring between the upper end of the battery and casing and adapted to be compressed by turning the casing into the socket.

In testimony whereof, I have signed this specification in the presence of two subscribing witnesses.

ADOLPH C. RECKER.
